UNITED STATES PATENT OFFICE.

JAMES H. RAND, JR., OF TONAWANDA, AND LE ROI E. HUTCHINGS, OF BUFFALO, NEW YORK, ASSIGNEES, BY MESNE ASSIGNMENTS, TO REMINGTON RAND INC., OF TONAWANDA, NEW YORK, A CORPORATION OF DELAWARE.

CARD INDEX OR RECORD DEVICE.

Application filed January 9, 1925. Serial No. 1,389.

This invention relates to card indexes of that kind in which a plurality of card holders or members are maintained in overlapping relation on a tray or support, with the edges of the card holders or members protecting one beyond another.

Indexes of this nature have been provided in which the card holders have an attaching portion adjacent one edge for releasably securing the holder to the tray or support, and a transparent sheath or pocket at the opposite or free and exposed edge which is adapted to receive an edge of a card or an insert slip bearing data relating to the card to enable the data thereon to be viewed. The pockets on some of these holders are adapted to receive a card on each face of the holder, but as only one card is arranged on each side of the holder, the capacity of an index of this kind is limited, and where the index matter comprises a mass of brief records, such as names and addresses, the cost of providing a holder and a card for each name and address is expensive, and the capacity of each tray or support is limited. On the other hand, it is impractical to enter a plurality of names or records on a single card as only one of the records would be visible without moving the holders above it, and such a system lacks flexibility, as it is impracticable to rearrange the names when it is desired to add new names or records, except by providing new cards and reentering all the previous data.

Some objects of the present invention therefore are to provide a card index of relatively great capacity having a series of card holders arranged in overlapping relation with their edges exposed one beyond another, and a plurality of groups or series of overlapping cards also arranged with their edges exposed one beyond another, said holders and card groups being constructed so that each holder is adapted to support one or more of said groups of cards; also to provide a holder of this kind having means for visibly indicating the nature of the data on the cards of each group, or the location of a particular card having certain data thereon, without the necessity of disturbing the holders until the holder bearing such card has been visibly located.

Other objects are to provide a card index

in which the individual cards of each group are constructed so as to be interlocked or detachably connected to each other and so that any one of the cards comprising an end card of a group can be detachably connected to any holder of the series; also to construct the cards and holders so that the index is exceedingly flexible or adapted to be expanded whereby the individual cards, the groups of cards, or the card holders with or without the cards thereon may be readily interchanged, also to provide an index of this sort of such relatively great capacity that data heretofore requiring a large number of cabinets wherein to house the trays or support may be arranged in an index small enough to be confined in a fraction of the space previously required.

Another object is to provide an index of this sort with holders or members having means thereon for protecting the faces of the cards in use and preventing the edges of the cards of one group or holder from catching on the cards on another holder and which is movable to permit access to the cards; also to improve card indexes in the other respects hereinafter specified and claimed.

In the accompanying drawings,

Fig. 1 is a fragmentary plan view of an index tray or support, and a plurality of holders or members with groups of cards or index devices supported thereon and embodying one form of the invention.

Fig. 2 is a fragmentary face view of one of the holders detached and showing card groups on each face thereof.

Fig. 3 is a transverse section thereof on line 3—3, Fig. 2.

Fig. 4 is a face view of a slightly modified form of the record cards or members showing two of the cards partly attached.

Figs. 5 and 6 are similar views showing the front and rear faces respectively of the two cards attached.

Fig. 7 is a transverse section thereof on line 7—7, Fig. 6.

Fig. 8 is a fragmentary face view of a group of the index cards arranged on a holder having means for protecting the cards from wear.

Fig. 9 is a similar view showing a number of the holders of Fig. 8 arranged on a tray or support.

Fig. 10 is a view showing a group of cards of modified form and a card holder for supporting these cards.

Fig. 11 is a similar view showing a group 5 of the cards arranged on an intermediate card, one of said card groups and cards being arranged on each face of a holder.

Fig. 12 is a face view of a card holder of modified form and a plurality of cards secured thereon.

In the various forms of the index shown in the drawings, a plurality of card holders or devices 10 of well known form are provided, each having a body portion 11 which is hinged to a relatively narrow portion 12 secured to an attaching member 13. The attaching member is provided with lateral tongues 14 by which the holder is removably secured to a support or tray 15, as by inserting the tongues 14 beneath side flanges or retaining parts 16 at opposite sides of the tray. The holders 10 are adapted to lie flatwise on the tray with their body portions one above another and their free or lower edges 18 exposed one beyond another, by inserting the upper edges or portions of one holder between the portions 12 and 13 of the holder above. The holders are preferably provided with transparent sheaths or pockets 19 at their lower edges. The invention, however, is not limited to use with holders lying substantially flatwise on a tray or support, as other holders having a body portion and a portion which permits the body portion to swing or hinge thereon may be used, as long as they are adapted to be arranged in overlapping relation.

According to the present invention the index matter or other data to be carried on the holders 10, such for example as an alphabetical list of names, addresses or the like, is inscribed on a series of cards or index devices, preferably one name or entry to each card, and these cards are adapted to be arranged vertically in groups, series or chains and maintained in substantially fixed overlapping relation with one edge of each card exposed beyond the edge of the adjacent cards to display the index matter thereon, and means are provided whereby one or more of these groups may be detachably secured to and rest flatwise on the body portion of each holder 10 so that when the holders are arranged in nested relation as explained the groups of cards are disposed or lie between and are concealed by the body portions of adjacent holders but are readily accessible by swinging the holders on their hinges.

In the construction shown in Figs. 1-9 60 the cards 20, having upper and lower parallel edges 21, 22 respectively, are each provided with a pair of oppositely directed tabs or ears 23 formed by cutting away a portion at each end of the card near the upper corners. 65 Each card also has a pair of apertures or

slots 24 formed between the upper and lower edges and spaced so that the tabs 23 of one card may be inserted in the slots 24 of another card so as to lie flat thereon and permit the upper portion of the card to which it is attached to be exposed. These exposed portions are intended to receive the index notations or entries 25. It will be seen that the cards 20 may be detachably secured together by the tabs 23 and slots 24 to form 75 unitary groups 26 of any desired length.

While the cards 20 shown in the drawings are relatively narrow, wider cards may of course be used if desired, in which case a less number of cards would be used to comprise a group.

As the tabs 23 of the upper cards of a group are unattached to the other cards, this card is preferably utilized for attaching the group of cards to the holder 10, and for this purpose the holder body 11 is provided with a pair of slots 28 preferably near the hinge connection or upper edge, for said reception of the tabs 23 of the upper card, whereby the group of cards is detachably secured to lie flat on the holder. In the construction shown in Figs. 1, 8 and 9, a pair of card groups, series or chains 26 is arranged side by side on the front face of each holder 10, while in Figs. 2 and 3, a pair of groups 26 is arranged on each face of each holder, but one group only, or as many groups as desired may be carried on each holder.

The holders 10 are provided with suitable means for indicating the nature of the index matter thereon, and preferably each holder is provided with means whereby the user of the index can determine the approximate location of any desired record by visual observation, or in other words, the group in 100 which the desired card is located can be determined by such means. For this purpose removable slips 30 are provided, one of which is adapted to be inserted in the exposed transparent pocket 19 of each holder in Figs. 1, 8 and 9 or one in the pocket at opposite sides of the holder if cards are secured on both faces thereof as in Figs. 2 and 3. These slips bear index matter or other suitable data indicative of the records on the groups of 105 cards. For instance, as shown in Figs. 1 and 9 the cards in the two groups on each holder 10 bear names arranged in alphabetical order, and the slips are inscribed with the first name of the first group and the last name of the second group, thereby apprising the user that any name, which by its spelling, comes between these two names will be found in one or other group on that holder, and may be exposed by swinging the holders 110 above it backwardly on their hinges.

As shown in Figs. 10 and 11, an arrangement is provided whereby the cards are disposed in groups as before, but wherein each of the cards of each group, instead of only 115

an end card, is engaged or connected with the holder, and the lower edges of the card are exposed for the reception of index or like matter. In this construction each of the cards 31 is slit or cut to form an integral central flap 32 having laterally and oppositely directed lips or tongues 33. The cards are adapted to be attached to the holders 10^a by inserting the tongues 33 into the vertical parallel slots 34 in the holders and are nested so as to expose their lower edges by guiding the cards after they have been connected as explained, so as to engage the upper edge of one card between the flap 32 and main portion of the card above. This arrangement provides a compact grouping of the cards on the holders and permits any one or more of the cards to be removed, or others added without detaching the remaining cards from the holder. This type of index is particularly adapted for use in an index wherein the data is of a more or less temporary character and is to be frequently changed or enlarged.

Another arrangement of the card groups is illustrated in Fig. 12 wherein cards 36 similar to those shown in Figs. 1-3, 8 and 9 but without the slot 24 are used. The holder 10^b in this instance is formed so that the cards 36 are separately attached thereto and maintained in fixed overlapping relation thereon, as by providing two parallel, vertical rows of spaced slots 37 for the reception of the tabs 38 of the cards. While the cards 36 are disposed in overlapping relation, any one or more of the cards may be removed without disturbing the others, and a portion only of a group may be attached and securely maintained on the holder, and other cards added at any time.

It may be found necessary or desirable to form the cards or index members of paper or other relatively thin and flexible material which might cause the cards to bend between their points of attachment and become disengaged from one another or from the holders, or the cards may bulge between their ends and be prevented from lying flat in the index. Means are provided whereby such cards are held in interlocking engagement at one or more points intermediate of their ends or side edges. This means, see Figs. 4-6, comprises an ear or lip 40 formed by slitting or cutting each card along the line 41, at a point preferably midway between its side edges and in a position which will coincide substantially with the bottom edge of an adjacent card when the cards are assembled. When the cards are arranged on the holders, or are connected in groups, each lip 40 is adapted to be sprung over the coincident edge of the adjacent card as shown in Figs. 5 and 6, thereby holding the middle portions thereof securely in position and maintaining the cards flat on the holders.

and preventing them from becoming unintentionally disengaged.

It is desirable, but not essential, that means be provided for protecting the groups of cards against wear and preventing the cards in one group or on one holder from catching on the cards on another holder in the use of the index. The present invention includes means for this purpose, see Figs. 8 and 9, each holder 10 being provided with one or more protecting strips or sheet separators 45 of thin, flexible and preferably transparent material such as celluloid, secured at or adjacent an edge of the body portion 11 so as to extend lengthwise of and upon each group of cards. In the embodiment illustrated each holder is provided with two of the strips 45 for each group of cards and these strips are secured at their lower ends only to the lower edge portion of the holder on a line below the lower edge of the bottom cards, as by wire staples or stitches 46, so as to extend upwardly over and in contact with the card groups. When the card holders lie in substantially vertical planes, the celluloid strips 45 lie flat on the cards because of the stiffness of the celluloid and because said strips are confined by the overlying card holder. These strips effectively prevent undue wear on the cards in the use of the index, thus prolonging the life thereof, and as they may be easily turned back as shown in Fig. 8, they afford ready access to the cards and, being transparent, the legibility of the records is unimpaired by their use. Any other suitable protecting means may be employed which will permit proper visual observation of, or ready access to, any of the cards on the holders.

While several forms of cards adapted for use in groups in accordance with this invention have been illustrated and described, it will be noted that in each case the card groups, having the cards arranged in overlapping relation with an edge or portion of each card exposed beyond the edges of adjacent cards, are mounted on holders which in turn are also disposed in overlapping relation with their edges exposed one beyond another.

We claim as our invention:

1. In an index device, a support, a plurality of plane holding members each adapted to be supported by one edge in overlapping relation on said support with their opposite edges exposed one beyond another, a plurality of separate index cards or members adapted to be arranged in groups or chains in overlapping relation with their edges exposed one beyond another, and means for detachably securing one or more of said groups of cards on each of said holders.

2. In an index device, a plurality of holding members each having a plane body por-

- tion and a flap at one edge adapting said holders to be arranged in overlapping nested relation with their opposite edges exposed one beyond another, a plurality of 5 separate index cards or members adapted to be arranged in groups or chains in overlapping relation with their edges exposed one beyond another, and means for detachably securing one or more of said groups of cards 10 on each of said holders.
3. In an index device, a support, a plurality of plane holding members having means for detachably connecting them to said support in overlapping arrangement 15 with edges of adjacent holders exposed one beyond another, a plurality of separate index cards or members, and means for detachably connecting a plurality of said cards in an overlapping series to each of said 20 holders.
4. In an index device, a support, a plurality of plane holding members having means for detachably connecting them to said support in overlapping arrangement 25 with edges of adjacent holders exposed one beyond another, a plurality of separate index cards or members, cooperating means on said cards and said holders whereby said cards may be attached in groups in overlapping relation and detachably supported on 30 said holders.
5. In an index device, a support, a plurality of plane holding members having means for detachably connecting them to said support in overlapping arrangement 35 with edges of adjacent holders exposed one beyond another, a plurality of separate index cards or members, opposite laterally extending attaching portions on each of said cards, and cooperating receiving portions on each of said holders, adapting said cards to be arranged and supported on said holders in groups in overlapping relation with their 40 edges exposed one beyond another.
- 45 6. In an index device, the combination with a plurality of holding members each having a plane body portion and a flap at one edge adapting said holders to be arranged in overlapping nested relation with their opposite edges exposed one beyond another, of a plurality of separate index cards or members adapted to be arranged flatwise in groups and in overlapping relation with their edges exposed one beyond another, and attaching means adapted to permit one or 50 more of said groups to be detachably secured on each holder so as to lie flatwise on and be backed by said body portion thereof.
- 55 7. In an index device, the combination with a support, and a plurality of holding members each having a flap provided with portions for securing said holder on said support in overlapping relation with adjacent holders so that their edges are exposed one beyond another, of a plurality of sepa- 60
- rate index cards or devices adapted to be arranged in groups in overlapping relation with their edges exposed one beyond another, a plane body portion on each of said holders of a size such that one or more of 70 said groups may lie thereon and be backed up and supported thereby, and means for detachably securing said group or groups on said body portion.
8. In an index device, a plurality of holding members each having a plane body portion and a flap at one edge adapting said holders to be arranged in overlapping nested relation with their opposite edges exposed one beyond another, a plurality of 75 separate index cards or members adapted to be arranged in groups in overlapping relation with their edges exposed one beyond another, means for detachably securing one or more of said groups of cards on each of 80 said holders, and the exposed edges of said holders being adapted to bear index matter indicative of the index matter on the cards in said group.
9. In an index device, a plurality of holding members each having a plane body portion and a flat at one edge adapting said holders to be arranged in overlapping nested relation with said body portions disposed substantially flatwise on said support with 85 their edges exposed one beyond another, a plurality of separate index cards or members adapted to be arranged substantially flatwise in groups in overlapping relation with their edges exposed one beyond another, means for detachably securing one or more of 90 said groups on each of said holders so as to lie on the body portion thereof and be concealed between the same and the body of another holder, and said exposed edges of said 95 holders being adapted to bear visible index data indicative of the index matter on said concealed card groups.
10. In an index device, a support, a plurality of plane holding members having 100 means for detachably connecting them to said support in overlapping arrangement with edges of adjacent holders exposed one beyond another, a plurality of separate index cards or members adapted to be arranged flatwise in groups in overlapping relation, means for detachably securing one or more of said card groups on each of said 105 holders, and each of said holders having one or more flat, flexible protecting members attached adjacent an edge thereof and adapted to extend over and lie upon said card group or groups to protect the same from wear in the use of the index.
11. In an index device, a support, a plurality of plane holding members having 110 means for detachably connecting them to said support in overlapping arrangement with edges of adjacent holders exposed one beyond another, a plurality of separate index cards or members adapted to be arranged flatwise in groups in overlapping relation, means for detachably securing one or more of said card groups on each of said 115 holders, and each of said holders having one or more flat, flexible protecting members attached adjacent an edge thereof and adapted to extend over and lie upon said card group or groups to protect the same from wear in the use of the index.
12. In an index device, a support, a plurality of plane holding members having 120 means for detachably connecting them to said support in overlapping arrangement with edges of adjacent holders exposed one beyond another, a plurality of separate index cards or members adapted to be arranged flatwise in groups in overlapping relation, means for detachably securing one or more of said card groups on each of said 125 holders, and each of said holders having one or more flat, flexible protecting members attached adjacent an edge thereof and adapted to extend over and lie upon said card group or groups to protect the same from wear in the use of the index.

- dex cards or members adapted to be arranged flatwise in groups in overlapping relation, means for detachably securing one or more of said card groups on each of said 5 holders, and each of said holders having one or more flat, flexible protecting members adapted to protect the same from wear in the use of the index, said protecting members each comprising a thin, flexible strip, 10 means for securing the same to the holder adjacent an edge thereof and so as to extend across and lie upon the cards, and said members being adapted to be flexed to permit access to said cards.
12. In an index device, a support, a plurality of plane holding members having means for detachably connecting them to said support in overlapping arrangement with edges of adjacent holders exposed one 20 beyond another, a plurality of separate index cards or members adapted to be arranged flatwise in groups in overlapping relation, means for detachably securing one or more of said card groups on each of said holders, 25 and each of said holders having one or more flat, flexible protecting members adapted to protect the cards from wear in the use of the index, said protecting members each comprising a thin, flexible strip, means for securing the same to the holding member adjacent an edge thereof and so as to extend across and lie upon the cards, said members being transparent and flexible to permit index matter on said card groups to be viewed 30 without moving said members, and to permit said members to be flexed to afford access to said cards.
13. In an index device, a support, a plurality of plane holding members having means for detachably connecting them to said support in overlapping arrangement with edges of adjacent holders exposed one 40 beyond another, a plurality of separate index cards or members, means for detachably securing said cards to each other in groups in overlapping relation, said means comprising a pair of oppositely disposed lugs on each card, each card having corresponding apertures adapted to receive the respective 45 lugs of another card, and each of said holders having a pair of spaced apertures adapted to receive a pair of said card lugs to detachably support a group on said holder.
14. In an index device, a support, a plurality of plane holding members having means for detachably connecting them to said support in overlapping arrangement with edges of adjacent holders exposed one 55 beyond another, a plurality of separate index cards or members, means for detachably securing said cards to each other, comprising a pair of oppositely disposed lugs on each card, each card having a pair of corresponding apertures adapted to receive the 60 respective lugs of another card, and said 65 apertures being disposed so that said cards, when connected will be arranged in groups in overlapping relation with their edges exposed one beyond another, and each of said holders having a pair of apertures adjacent one edge and adapted to receive the lugs on one of said cards to detachably support a group on the holder, and a flexible protecting strip attached to the opposite end of said holder and adapted to extend across said 70 group to protect the same.
15. In an index device, a support, a plurality of plane holding members, having means for detachably connecting them to said support in overlapping arrangement 75 with edges of adjacent holders exposed one beyond another, a plurality of separate index cards or members, a pair of opposite, laterally extending lugs, one of the lugs being disposed on one side of the card and the other lug on the other side of the card; and said cards each having spaced apertures at their side portions to receive the respective lugs of another card to maintain said cards in overlapping spaced relation in 80 groups, and an ear on each card intermediate the side edges thereof adapted to engage over one edge of an adjacent card to hold the cards flatwise one on another, and said holders having apertures adapted to 85 receive the lugs of one of said cards to detachably support a group of cards thereon.
16. In an index, a plurality of interengaging index cards or members arranged in groups in overlapping relation with their edges exposed one beyond another, a plurality of supports on which one or more of said groups is or are adapted to be arranged, sheet separators on said supports arranged between the groups on adjacent supports 90 and adapted to prevent wear between said groups when said groups are moved relatively to each other or to their supports.
17. In an index device, a series of similar cards superimposed one on the other with their edges in offset relation so as to form a series or chain of cards with edges in visible index position, interlocking means for detachably maintaining said cards in chain 95 form, and a holder member adapted to engage end cards of each chain so as to support a plurality of chains of cards.
18. In an index device, a series of similar cards superimposed one on the other with their edges in offset relation so as to form a series or chain of cards with edges in visible index position, interlocking means for detachably maintaining said cards in chain 100 form, a holder member adapted to engage end cards of each chain so as to support one or more chains of cards, and frame means for supporting a plurality of said holder members superimposed one on the other with the edges of said holder members in 105 offset, visible, index position.

19. In an index device, a card having a plurality of outstanding ears and a plurality of openings, the ears of one card being adapted to register with and enter into the openings of another similar card so as to form a series or chain of cards with overlapping edges in visible, index position, a holder member having openings adapted to receive the ears of a card in said chain so as to support a plurality of chains of cards on said holder member in parallel relation.
20. In an index device, a card having a plurality of outstanding ears and a plurality

of openings, the ears of one card being adapted to register with and enter into the 15 openings of another similar card so as to form a series or chain of cards with overlapping edges in visible, index position, a holder member having openings adapted to receive the ears of a card in said chain so 20 as to support one or more chains of cards on said holder member, and frame means for supporting said holder members in overlapping visible, index position.
